UNITED STATES PATENT OFFICE.

FRANCIS B. KENDALL, OF MONMOUTH, ILLINOIS, ASSIGNOR OF TWO-THIRDS
TO CASPER M. DULL AND MARK M. LUCY, OF SAME PLACE.

COMBINED PULVERIZER, SEEDER, AND HARROW.

SPECIFICATION forming part of Letters Patent No. 404,285, dated May 28, 1889.

Application filed February 1, 1889. Serial No. 298,375. (No model.)

To all whom it may concern.

Be it known that I, FRANCIS B. KENDALL, a citizen of the United States, residing at Monmouth, in the county of Warren and State of Illinois, have invented certain new and useful Improvements in Combined Pulverizer, Seeder, and Harrow; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to certain new and useful improvements in combined seeders and harrows, and it has for its object to simplify and cheapen and render more efficient and durable this class of devices.

20 The invention consists in the peculiar combinations and in the novel construction, arrangement, and adaptation of parts, all as more fully hereinafter described, shown in the drawings, and then specifically defined in the appended claims.

25 The invention is clearly illustrated in the accompanying drawings, which, with the letters of reference marked thereon, form a part of this specification, and in which—

30 Figure 1 is a perspective view of a combined seeder, clod-crusher, and harrow constructed in accordance with my invention. Fig. 2 is an enlarged perspective view, with parts broken away, of the cylinder detached. Fig. 3 is a similar view of the rotary disk attachment. Fig. 4 is a bottom plan of Fig. 1. Fig. 5 is a rear view, and Fig. 6 is a longitudinal section upon the line $x-x$ of Fig. 4.

Similar letters of reference indicate like parts throughout the several views.

Reference now being had to the details of the drawings by letter, A designates a suitable rectangular frame composed of the transverse bars or sills a , joined together in any well-known way, and preferably covered to form a platform, A', although this platform may be sometimes omitted, if desired.

Secured to or formed integral with the longitudinal bars a' , upon the under side thereof, are the brackets or bearings A ^{2} , in which are journaled the pintles or axles b of

the clod-crushers B, each of which consists of a drum, B', and the spuds or projections b' , secured in sockets or openings in said drum and extending beyond the periphery thereof, 55 as shown.

B ^{2} is the tongue secured to the transverse sills a , as shown.

The end longitudinal bars, a' , are extended beyond the forward longitudinal sill, and 60 have secured thereto the depending lugs or brackets c , in the lower end of which is journaled the feed-roller D in any well-known way. The pintle of this roller at one end is extended, as shown at c' , and on this 65 extended end is secured a grooved pulley, c^2 , around which and a smaller grooved pulley, d^2 , on the extended end of the pintle of one of the crushers B passes an endless belt or cord, d^4 , so that by the revolution of the crusher 70 the feed-roller is revolved.

While I have shown a belt or cord and grooved rollers as the connection between the crusher and feed-roller, I do not wish to limit myself thereto, as it is evident that other 75 means might be employed—as a sprocket-chain and wheels—with the same result.

The lugs or brackets c form the ends of the seed-box, and to these lugs or brackets are secured the sides e of the box, which may be of 80 any suitable construction or material. These sides extend down to about the center of the feed-roller, and between their ends are secured to the central partition, e' , the lower end of which is formed with a curved recess to 85 conform to the curvature of the feed-roller. Inside the box and secured to the ends thereof are the plates e^2 , the lower ends of which are also provided with curved recesses to receive the feed-roller, like the central portion. 90

The feed-roller is provided with a plurality of recesses or pockets, f , four rows being shown in the drawings; but I do not wish to be restricted to that number. In these recesses or pockets I secure the screws f' , and 95 by adjusting them in or out I can regulate the amount of feed of the seed.

The lower ends of the central partition and the end plates of the box are cut away upon opposite sides to receive the cut-offs g , which 100 consist of rectangular bars secured therein by the engagement of the same with the sur-

rounding walls of the parts, and these bars serve to even off the seat, they removing all seed in the revolution of the roller, excepting that contained in the pockets *f*, as will be 5 readily understood.

F are a series of spring fingers or cleaners secured at one end to the rear longitudinal sill of the frame, with their free ends projecting downward and forward between the 10 projections or spuds on the crushers and serving to prevent the same from clogging.

Sleeved on the pintles of the crushers, and prevented from end displacement in an outward direction by the bearings *A*², are the 15 arms *G*, which extend rearward and have detachably secured thereto the cross-bars *H*, provided with the harrow-teeth *h*, secured thereto in any well-known manner.

In order to enable me to raise and lower the 20 harrow-frame, I provide the following mechanism: Journalized in suitable bearings or boxes, *i*, on the rear end of the transverse sill of the frame is the crank-shaft *j*, having one end extended rearward to form the arm *j'*, the 25 end of which is bent at right angles, as shown at *j*², while the other end is bent into a curve, *j*³, from whence it extends upward and forward to form the hand-lever *J*. Secured to one of the bars of the harrow-frame is the 30 substantially U-shaped piece of metal *K*, the upright portions of which are provided with a plurality of holes, *k*, and in two of these holes is placed the transverse pin or bolt *l*, on which is hung one end of the link or connecting-bar 35 *m*, the opposite end of which is formed with an eye, *n*, designed to detachably receive the portion *j*³ of the operating-lever. By means of this connection the harrow-frame may be raised and lowered at will from the driver's 40 seat.

A ratchet-bar, *L*, is secured to the platform, or to the sills of the frame if a platform is not used, in suitable position to engage the operating-lever to hold the harrow-frame in 45 its adjusted position, in a manner well understood.

The plurality of holes in the piece *K* are for the purpose of changing the throw of the lever when occasion requires. The seat *M* is 50 of the shape shown, and is held to the platform or the longitudinal sills of the frame in the following manner: *o o* are substantially U-shaped pieces of metal, the cross-bars of which are passed loosely through holes in the seat 55 and the ends of the wire secured in the platform or sills, as shown. By this mechanism the seat may be turned or moved forward or back on its supports to raise or lower the seat, the weight of the occupant serving to 60 hold the said seat in its adjusted position without other means. In Fig. 3 of the draw-

ings I have shown a rotary disk or cutter attachment designed to be used substantially in place of the harrow-tooth bars. It consists of the two bars *N*, (more may be employed, however, if desired,) each bar being provided with a plurality of holes extending vertically therethrough, and in each hole is a shank held at its upper end by means of a peg, *p*, and at its lower end provided with a 65 head, *p'*. Around each shank between the head thereof and the under side of the bar is a holder, *q*, between the ends of which is journaled the support for a rotary disk or cutter, *r*. This attachment is for the purpose 70 of cutting up the sod before it is plowed. After it is plowed the harrow-tooth bars are substituted for the cutter attachment, the two being made interchangeable for the purpose. 75

The cutters or the disks of the cutter attachments are preferably, though not of necessity, arranged as shown—that is, so that the cutters of one bar will travel in the space between two cutters of the bar, so as to cut the sod into smaller pieces. 80

Hinged to the inner bar of the harrow-frame at the ends thereof are bars *O*, carrying the markers *P*, each of them so arranged as to swing from a horizontal to a vertical position, the free ends of the levers being 90 connected by a chain or cord, *Q*, which is passed through an eye or loop, *s*, on the seat, and of such length that when one of the markers is horizontal or in a working position the other will be vertical, as shown, and vice 95 versa. By this arrangement the markers can be manipulated from the seat, so that the driver can straddle the mark and watch the seed that is being sown and see that there are no misses. In going in one direction the 100 marker upon one side is down, and in going in the opposite direction the other marker is used.

Having thus described my invention, what I 105 claim as new is—

The combination, with the frame and the harrow-frame, of the operating-lever journaled on the frame and formed with rearwardly-extending arm and right-angled portion *j*², the U-shaped piece on the harrow-frame, provided with a plurality of holes, *K*, and the links pivotally connected at one end with said piece and adjustable vertically, and at the other end formed with an eye, *n*, to receive the end of the portion *j*³, substantially 110 as and for the purpose specified.

In testimony whereof I affix my signature in presence of two witnesses.

FRANCIS B. KENDALL.
